UNITED STATES PATENT OFFICE

2,542,683

CHARACTERIZED SLIDE CALENDAR

William Lang, Verona, N. J., assignor to The Bates Manufacturing Company, Orange, N. J., a corporation of New Jersey

Application November 10, 1948, Serial No. 59,319

14 Claims. (Cl. 40—109)

1

In general, the calendar comprises a month table upon which are indicated the days of the month, a day of the week strip upon which are printed or otherwise formed inscriptions indicating the days of the week, a month strip upon which appear the names of the months in proper sequence, and a year band which carries groups of numerals in proper sequence to represent a plurality of years, with which are associated inscriptions representing the days of the week upon which fall the first days of the months of the corresponding year; and a prime object of the invention is to provide a novel, simple and easily operable construction, combination and compact arrangement of the month table, day of the week strip, month strip and year band.

Another object is to provide a calendar or date finder of the character described which shall include a housing having a sight opening or window therein, and novel and improved means for mounting said month strip and said year band within said housing and for operating or moving said month strip and said year band relatively to each other to locate the inscriptions thereon selectively for exposure through said sight opening or window.

A further object is to provide in such a calendar novel and improved means for mounting and operating the month table within said housing and for display of the inscriptions thereon selectively through said sight opening or window.

Other objects are to provide a calendar which shall be relatively inexpensive in construction and attractive in appearance; and to obtain other advantages and results that will be brought out by the following description in conjunction with the accompanying drawings, in which

Figure 1 is a front elevational view of a calendar constructed in accordance with the invention;

Figure 2 is a central vertical longitudinal sectional view of the calendar;

Figure 3 is a transverse vertical sectional view, approximately on the plane of the line 3—3 of Figure 1;

Figure 4 is a similar view, approximately on the plane of the line 4—4 of Figure 1;

Figure 5 is a horizontal sectional view of the complete calendar, taken approximately on the plane of the line 5—5 of Figure 3;

Figure 6 is a similar view, approximately on the plane of the line 6—6 of Figure 3;

Figure 7 is a fragmentary rear elevational view of portions of the month table, the month table back and the month table holder, showing the manner of assembling and connecting said parts;

Figure 8 is a similar view of said parts from the front thereof;

Figure 9 is a front elevational view of the day of the week strip;

2

Figure 10 is a similar view of the month table in extended or flat condition;

Figure 11 is a front elevational view of the month strip in extended or flat condition;

Figure 12 is a transverse vertical sectional view, approximately on the plane of the line 12—12 of Figure 11, and

Figure 13 is a front elevational view of the year band in extended or flat condition.

10 Specifically describing the illustrated embodiment of the invention, the reference character A designates the housing of the calendar which may be conveniently formed of sheet metal or a synthetic plastic composition and includes a base or bottom wall 1 having upstanding front and rear flanges 2, end walls 3 having inturned flanges 4, and a cover 5 which forms in effect the top, front and rear walls of the housing and is held in position between the bottom wall 1 and the flanges 4. The cover may be shaped as desired, but as shown, provides upwardly and rearwardly or inwardly inclined front and rear walls 6 and 7, respectively, and a convex arcuate top wall 8.

15 25 The front wall 6 is provided with a sight opening or window 9 in which, preferably, is a transparent sheet 10 of suitable material, for example, glass or a plastic composition, which is disposed between the front wall and an inverted U-shaped window frame 11 having an upper cross-piece 12 extending across the window opening in spaced relation to the upper edge thereof, and side pieces 13 disposed along the vertical edges of the window opening and secured to the front wall in 30 any suitable manner as by spot welding along the edges of said side pieces. Mounted on the cross-piece 12 as by adhesive and disposed between it and the transparent sheet 10 is a day of the week strip B which has letters thereon representing the days of the week, Sunday to Saturday, inclusive, arranged in proper sequence.

35 40 Also extending across the window opening so as to be displayed therethrough, is the month table C which comprises a piece of flexible material, for example, thin paper, and which has a backing sheet 14 formed of suitable material, such as linen. The month table C and said backing are secured to and operable by a holder formed of any suitable material, preferably metal, and generally designated D. This holder is shown 45 50 as comprising a body portion in the form of a plate 15 underlying the backing sheet 14, as best shown in Figures 3, 7 and 8, and having an operating arm 16 projecting through openings in the backing sheet and the month table. Tabs 17 and 18 are formed at about the middle of the length of the upper and lower edges of the month table, respectively, and the lower tab 17 is folded 55 around the edge of the plate 15 and the backing strip. The lower edge of the plate 15 has ears 19

extending through holes 20 in the tab 17 and clinched against the said tab at the rear of the backing sheet. The upper tab 18 is folded downwardly around the upper edge of the backing sheet and has an opening 21 through which passes an ear 22 on the upper edge of the plate 15 which is clinched over the tab at the rear of the backing sheet. The operating arm 16 projects through a slot 23 between the lower edge of the transparent sheet 10 and the upper edge of the front flange 2 of the housing, and has a finger-piece 24 whereby the holder can be slid horizontally so as to move the month table across the window opening.

For guiding the month table I have shown a guide frame E formed of any suitable material and best shown in Figures 2 and 6, said frame comprising a straight main portion 25 disposed in spaced and approximately parallel relation to the rear wall of the housing and having protuberances 26 on its rear side to engage the inner surface of said rear wall. At the ends of the main portion 25 are guide arms 27 that extend forwardly in spaced relation to the end walls of the housing and have perforate ears 28 that are secured to the bottom walls of one of the housings by clinched tongues 29. The lower portions of the ends of the month table and the backing sheet are disposed in slidable relation to the inner surfaces of the guide arms 27 and the main portion 25 so as to positively guide the month table when it is slid in either direction by the operating finger-piece 24, as best shown in Figure 5.

Cooperating with the guide frame E is a front guide frame F behind and supporting the month table C and secured to the bottom wall of the housing by integral perforate ears 30 through which are clinched tongues 31 on the bottom wall of the housing. Said frame F has upwardly extending side arms 32 at the upper ends of which are fingers 33 overlying the upper edges of the transparent sheet 10, the window frame 13 and the month table C.

The month table has on its face numerals 34 representing the days of the month which are arranged in vertical columns horizontally spaced in accordance with the spacing of the indications 35 of the days of the week on the day strip B, and with this construction it will be observed that by manual manipulation of the operating arms 16 through the finger-piece 24, the month table may be moved horizontally relatively to the window opening and to the day strip B so as to locate any selected vertical column of the numerals 34 in vertical alinement with and beneath any selected indication 35 on the day strip.

The month strip G is formed of any suitable flexible material and has imprinted or otherwise formed thereon the names 36 of the months, said strip being mounted for movement vertically behind the month table so as to expose selectively the name of the various months through the window between the top of the day strip and the upper edge of the window opening, as best shown in Figure 1. For mounting and moving the month strip, a spacer-guide 37 is mounted near the top wall of the casing of the housing in any suitable manner, for example, by tongues 38 on the spacer guide that extend through openings in the end walls 2 of the housing and are clinched to fixedly mount the spacer on and between said end walls. The month strip is bent over this spacer and is held in contact therewith by guide fingers 39, one end of the strip extending toward the rear wall and the other end extending downwardly and for-

wardly behind the month table C and having at its lower end an eyeleted opening 40 through which projects a finger 41 on an actuating arm 42 which is connected to an operating shaft 43 journaled in an opening in one end wall of the housing and having a knob or finger-piece 44 mounted thereon and accessible outside the housing. As shown, the shaft 43 has a portion that is polygonal in cross-section and which extends through a slot 45 in the arm 42 that may be conveniently formed by stamping out a portion 46 of the arm, as shown in Figures 2 and 4. This portion 46 and the end portion 47 of the arm 42 snugly contact with opposite sides of the polygonal portion of the shaft 43, while the edges of the slot 45 snugly engage the other sides of the shaft 43, as shown in Figure 4, so that said arm 42 is constrained to rotate with the shaft.

With this construction, it will be observed that by manually rotating the finger-piece 44, the arm 42 may be swung in an arc concentric with the axis of rotation of the shaft 43 and thereby slide the month strip G longitudinally over the spacer-guide 37. In order to more positively guide the month strip and the arm 42, a guide element 48 that is preferably channel-shaped in cross-section is secured to the bottom wall 1 of the housing with its side flanges 49 vertically disposed, as best shown in Figures 2 and 5. The upper edges 30 of the flanges 49 are concavely curved, as shown in Figure 3, and disposed in vertically spaced relation thereto is a guide plate 50 which is secured to the bottom wall of the housing in any suitable manner, for example by an integral arm 51 having notches 52 in its edges into which are clinched ears 53 that project upwardly from the bottom wall of the housing. The month strip is threaded between said guide plate and the upper curved edges of the guide element 48, and preferably the arm 42 has a pair of lugs 54 which receive between them one of the flanges 49 of the guide element, thereby providing a positive guide for the swinging end of said arm and for the month strip.

In addition to the names of the months, the month strip also carries inscriptions 55 indicating the number of days in the corresponding months, except in the case of February where the month strip has a perforation 56 to register with numerals 57 on the year strip H which represent the number of days in the month of February in respective years that are indicated by the usual indicia i. e. numerals 58. The month strip also has a plurality of apertures 59, one for each month, to register with symbols 60 on the year strip H which represent respectively the days of the week upon which fall the first days of the months of the corresponding year, it being understood that the month strip is arranged in overlying relation to the year strip in juxtaposition to the window opening 9.

The indicia 58 of the years are arranged in succession longitudinally of the year strip adjacent one edge thereof, and the symbols 60 are arranged in horizontal lines or rows in alinement with the corresponding year indicia 58, all as best shown in Figure 13. Similarly, the indications 57 of the days in the month of February for various years are arranged in the same horizontal rows with the indicia 58 of the corresponding years. The year band is mounted for movement behind the month strip G, and the right-hand margin of the year strip bearing the year indications 58 extends beyond the corresponding edge of the month strip so as to display the year indications

through the window 9 above the day strip B and beyond the right-hand edge of the month strip, as shown in Figure 1. The apertures 59 in the month strip also expose the symbols 60 on the year strip through the window above the day strip, the position of the exposure or display depending upon the horizontal position of the respective apertures 59 which in turn, of course, correspond to the position of the symbol 60 on the year strip that corresponds to the day of the week on which falls the first day of the corresponding month in a certain year.

For mounting and vertically moving the year strip, the longitudinal edges of the strip are formed with rows of perforations 62 to receive the teeth of sprocket wheels 63 that are mounted on a shaft 64 which has a cylindrically reduced portion 65 at one end relatively rotatably fitted in a socket 66 in the operating shaft 43 for the month strip, and its other end fitted in a socket 67 of an operating shaft 68 which is journaled in an opening 69 in the end wall 3 of the housing in opposed and coaxial relation to the operating shaft 43. A finger-piece 70 is mounted on the end of the shaft 68 that projects from the housing.

The ends of the year strip are fastened together, for example, adhesively, as indicated at 71, and the year strip is mounted on the sprockets 63 in encircling relation to the shaft 64, as best shown in Figure 3, with a portion thereof disposed in close, preferably sliding, relation to the rear side of the month strip. The portion of the year strip that hangs below the sprockets 63 is supported and guided by the upper surface of the month strip guide plate 50. With this construction, it will be observed that the year strip can be moved to locate the inscriptions 58 and 60 selectively in proper juxtaposition to the window 9 and a selected inscription 36 on the month strip, by simple manual rotation of the finger-piece 70 in the proper direction.

It will be observed that the shaft 64 has the dual function of supporting the sprockets 63 and of connecting and holding the two operating shafts 43 and 68 against tilting out of proper coaxial alinement.

The shaft 43 is held against longitudinal displacement from the housing by the arm 42 and its lugs 54 engage the flange 49 of the guide element 48, while the shaft 68 may be held against longitudinal displacement from the housing by a spring 72 secured on the corresponding end wall 3 and yieldingly held in a groove 73 in the shaft.

It may be desirable to positively connect the two sprockets 63 together so that they may be handled as a unit for slipping them onto and off the shaft 64, and for this purpose I may utilize combined tie and spacer bars 74, and the shaft may be polygonal in cross-section to slidably fit correspondingly shaped holes in the sprockets.

In operation of the calendar or date finder, assuming it is desired to ascertain what day of the week Christmas, i. e. December 25th, falls on in the year 1951, the year strip knob 70 first will be rotated to display the year indication 58 for the year "1951" through the window above the day strip B, after which the month strip knob 44 will be rotated to expose the indication 36 on the month strip representing the month "December." The day of the week upon which the first day of the month will fall in the year 1951 will then be visible through the aperture 59 above the day strip B and to the left of the 75

month indication "December." Then the month table finger-piece 24 should be operated to move the month table so that the inscription 34 representing the first day of the month will be disposed in vertical alinement with the indication 35 on the day strip that corresponds to the day represented by the symbol 60 that is visible through the aperture 59 juxtaposed to the name of the month "December." Thus, the numeral "25" on the month table is disposed in vertical alinement with the "Tuesday" indication 35 on the day strip B, and therefore it appears that Christmas of 1951 will fall on Tuesday.

It will be understood by those skilled in the art that I have illustrated and described the now preferred embodiment of the invention, but that many modifications and changes may be made in the details of construction of the calendar or date finder within the spirit and scope of the invention.

Having thus described the invention, what I claim is:

1. A calendar comprising a housing having a rectangular window, a day of the week strip in spaced relation to the upper edge of said window and having horizontally spaced characters representing the names of the days of the week, a month table having vertical columns of numerals representing the days of the month and spaced horizontally correspondingly to said characters on the day of the week strip and visible through said window below said day strip, means for moving said month table horizontally across said window, a month strip behind said month table and said day of the week strip and carrying the names of the months which are arranged in vertically spaced relation and are individually visible through said window in the space between the upper edge of the window and said day of the week strip, means for moving said month strip vertically across said space, a year strip arranged behind said month strip and having indicia representing the years arranged consecutively in vertically spaced relation thereon and visible individually through said window in said space above said day of the week strip and beyond one edge of said month strip, said year strip also having symbols representing the names of the first days of the months of the respective years arranged in horizontal rows in alinement with said indicia respectively, and means for moving said year strip vertically, said month strip also having an aperture in horizontal alinement with each month name to expose the one of said symbols that represents the name of the first day of the corresponding month of the year corresponding to the same horizontal row of symbols.

2. A calendar as defined in claim 1, wherein said housing has a horizontal slot and said means for moving said month table comprises a holder connected to said month table and having a finger-piece projecting outwardly of the housing through said slot whereby upon horizontal movement of said finger-piece said month table will be moved horizontally across said window.

3. A calendar as defined in claim 2, wherein said month table is flexible and with the addition of a front guide secured in said housing having a plate portion in spaced opposed relation to said window around the ends of which said month table is flexed, and a rear guide secured in said housing having arms slidably engaged by the end portions of said month table.

4. A calendar as defined in claim 1, wherein

said means for moving said month strip comprises a shaft journaled on a horizontal axis in said housing and carrying an arm which is connected to one end portion of said month strip, and with the addition of spaced guide elements secured in said housing between which said end portion of the month strip is slidable.

5. A calendar as defined in claim 4, with the addition of a spacer guide in said housing over which the other end of said month strip is slidable.

6. A calendar as defined in claim 4, wherein said arm slidably engages one of said guide elements and is guided thereby.

7. A calendar as defined in claim 1, wherein said year strip has at least one row of longitudinal perforations, and wherein said means for moving said year strip comprises a shaft journaled in said housing on a horizontal axis, and a sprocket mounted on said shaft and having its teeth cooperatively engaging said perforations in the year strip.

8. A calendar as defined in claim 7, with the addition of a spacer guide in said housing overlying a portion of said year strip in juxtaposition to said sprocket for preventing disengagement of the year strip from the sprocket.

9. A calendar comprising a housing having a rectangular window, a day of the week strip in spaced relation to the upper edge of said window and having horizontally spaced characters representing the names of the days of the week, a month table having vertical columns of numerals representing the days of the month and spaced horizontally correspondingly to said characters on the day of the week strip and visible through said window below said day of the week strip, means for moving said month table horizontally across said window, a month strip behind said month table and said day of the week strip and carrying the names of the months which are arranged in vertically spaced relation and are individually visible through said window in the space between the upper edge of the window and said day of the week strip, a year strip arranged behind said month strip and having indicia representing the years arranged consecutively in vertically spaced relation thereon and visible individually through said window in said space above said day of the week strip and beyond one edge of said month strip, said year strip also having symbols representing the names of the first days of the months of the respective years arranged in horizontal rows in alignment with said indicia respectively, means for moving said month strip vertically comprising a stub shaft journaled in said housing to rotate about a vertical axis and having a recess at its inner end and a finger-piece at its outer end, an arm on said shaft having one end connected to one end portion of the month strip, means for vertically moving said year strip comprising a stub shaft journaled in said housing in coaxial relation to the first-mentioned stub shaft and having a socket in its inner end and a finger-piece at its outer end, a rod fitted in said socket in the second-mentioned stub shaft to rotate with said stub shaft and having its other end relatively rotatably mounted on said socket of the first-mentioned stub shaft, and means rotatable by said second-mentioned stub shaft and operatively connected to said year strip to vertically move said year strip upon rotation of said second-mentioned stub shaft.

10. A calendar as defined in claim 9, wherein

the last-mentioned means comprises sprockets mounted on and to rotate with said rod, and wherein said year strip has longitudinal rows of perforations to be engaged by the teeth of said sprockets.

11. In a calendar, a housing having a window in its front wall, a flexible month table in said housing and viewable through said window, and means for mounting and horizontally moving said month table comprising a front guide secured in said housing and having a plate portion in spaced opposed relation to said window between which and said window said month table is arranged, the end portions of said month table being flexed rearwardly around the ends of said front guide, a rear guide fastened in said housing and having opposed arms each in spaced relation to the ends of said front guide and along each of which one end portion of said month table is slidable, and a finger-piece connected to said month table, said front wall of the housing having a horizontal slot through which said finger-piece projects.

12. In a calendar, a housing having a window in its front wall, a month strip movable vertically in said housing and viewable through said window, and means for mounting and moving said month strip comprising a shaft journaled on a horizontal axis in said housing and having an arm, means connecting said arm to the lower end portion of said strip so that upon rotation of said arm said strip will be pulled longitudinally, two vertically spaced guide elements mounted in said housing with said end portion of said month strip slidable between them, the upper end portion of said strip extending upwardly, and a guide member in said housing over which said upper end portion of said month strip is slidable.

13. In a calendar as defined in claim 12, one of said guide elements has an upstanding flange formed with an upper arcuately concave edge concentric with said shaft, and said arm has spaced guide fingers slidably engaging opposite sides of said flange for guiding the arm.

14. In a calendar, a housing having a window in a wall thereof, an endless year band in said housing and viewable through said window, and means for mounting and moving said year band vertically across said window comprising a shaft journaled on a horizontal axis in said housing, a pair of toothed wheels thereon engaging said year band adjacent said window and guiding said strip along said wall, said year band being suspended on said toothed wheels and having a row of perforations to cooperate with the teeth of each wheel, whereby upon rotation of said shaft said year band will be moved circumferentially, a curved guide element below said toothed wheels and beneath and over which said year band slides, and a guide member above said year band and said toothed wheels and holding said year band in engagement with said toothed wheels.

WILLIAM LANG.
